INSULATED PAIL

Lancaster P. Clark, Jr., Fairfield, Conn., assignor to Bridgeport Moulded Products, Inc., Fairfield, Conn., a corporation of Connecticut

Application July 7, 1958, Serial No. 51,680

Term of patent 7 years

(Cl. D58—17)

Fig. 1 is a front elevational view of an insulated pail showing my new design;

Fig. 2 is a side elevational view thereof, with a portion thereof in section;

Fig. 3 is a top plan view thereof;

Fig. 4 is a vertical sectional view of the cover part of the insulated pail, taken along the line 4—4 of Fig. 3;

Fig. 5 is a vertical sectional view, taken along the line 5—5 of Fig. 4;

Fig. 6 is a fragmentary front elevational view on an enlarged scale of the upper forward portion of the insulated pail body and;

Fig. 7 is a horizontal sectional view on a further en-

larged scale, taken along the line 7—7 of Fig. 6.

The rear and side not shown are the same as the front and side, respectively, shown.

I claim:

The ornamental design for an insulated pail, substantially as shown and described.
